UNITED STATES PATENT OFFICE.

JOHN G. REBER, OF CHICAGO, ILLINOIS; OLIVE S. REBER, ADMINISTRATRIX OF SAID JOHN G. REBER, DECEASED, ASSIGNOR TO THE SEFTON MANUFACTURING COMPANY, OF CHICAGO, ILLINOIS, A CORPORATION OF INDIANA.

FOLDING BOX.

1,035,638.

Specification of Letters Patent. Patented Aug. 13, 1912.

Application filed May 31, 1905. Serial No. 263,163.

To all whom it may concern:

Be it known that I, JOHN G. REBER, a citizen of the United States, residing at Chicago, in the county of Cook and State of Illinois, have invented certain new and useful Improvements in Folding Boxes, of which the following is a specification.

My invention relates to folding boxes generally, but more particularly though not necessarily, to that type or character of folding box known as hat boxes, suit boxes and the like, and the object of my invention is to produce a novel construction and arrangement of folding box possessing merits and features of utility not found in boxes of the general character as now in use. The box is so formed as to be economical of the material or stock and also is so arranged as to be assembled or set up from its flat or collapsed form to a box form in an automatic manner by a simple manipulation consisting, in the present instance, in bringing the end walls toward each other. When so assembled or set up the box may be held in this condition by a suitable fastening means, and, without removing such fastening means, may be collapsed by a movement of the end walls the reverse of that referred to in assembling or setting up the box.

Other features of advantage and utility will be apparent from the description hereinafter given.

In the drawings, Figure 1 is a plan view of the blank from which the box is formed; Fig. 2 a plan view of the box in flat collapsed form; Fig. 3 a perspective illustrating the manner in which the box is set up by bringing the ends toward each other; Fig. 4 a perspective of the box set up ready for use, with the exception that the flaps on the end walls have not yet been brought down in place; Fig. 5 a plan view of the box lid in flat or collapsed form; Fig. 6 a detail view illustrating a modification as to the holding of the corner folds in proper position relative to the end walls without connection with the latter; Fig. 7 a plan view of one of the members of a so-called suit box embodying my invention; Fig. 8 a perspective view of a form of box modified as to its in-turned flaps; Fig. 9 a plan of the same box

in flat form; and Fig. 10 a detail view illustrating a method which may be adopted for threading or lacing the string or tape through the end walls of the box. Fig. 11 is a plan of a portion of a blank somewhat similar to that of Fig. 1, but illustrating a different method of folding of the corners. In the said drawings the score lines or lines of fold are indicated by a single line on each side of which are fainter shade lines; and slits are designated by a single sharp black line.

As hereinbefore stated, my invention is particularly applicable to such folding boxes commonly referred to as hat boxes, suit boxes, and the like, but it will be understood that my invention is not limited to such styles or types of boxes and it will also be understood that I contemplate employing my invention wherever applicable. However, for the purpose of affording a clear and definite disclosure of my invention, I have chosen to describe and illustrate it as embodied in a hat box and also in a suit box, the hat box being herein illustrated in Figs. 1 to 5 and 8 and 9, and the suit box in Fig. 7.

Referring to the embodiment of my invention as illustrated in Figs. 1 to 4, the box, which is here formed from a single blank, comprises a bottom 1, to which are connected or hinged the opposite side walls 2, 2 at the score lines 1^a, as well as the end walls 3, 3 on the score lines 1^b. In the box illustrated all the walls are of equal area, the designations "end" and "side" walls being adopted merely for convenience in description to distinguish one set of opposite walls from the other. The bottom and also the side walls may be made of any suitable dimensions according to the desired size or proportions of the box. At the corners of the blank are formed the pairs or sets of triangular corner folds 4 and 5 hinged to each other along an oblique or diagonal score line, the corner folds 4 being separated from the end walls 3 by the slits 6, while the corner folds 5 are hinged to the side walls 2. Each of the corner folds 4 is provided with an extension 7 and the walls 2 and 3 are provided on their outer edges with ex-

tensions or flaps 2^a and 3^a respectively. The score lines which form the flaps 3^a are shown in Fig. 1 as extended and defining the extensions 7. In the blank from which this figure of the drawing was taken such score lines were so extended. This is merely incidental and inessential.

In practice, the blank formed as just described is assembled or folded together for the use of the consumer or user in such manner as to appear in flat or collapsed form as in Fig. 2. In this process of folding, the side walls 2, 2 are turned over flat upon the bottom 1 and the corner folds 4, 5 are likewise turned over and inwardly upon the end walls 3, 3. In this operation, the corner folds are turned at an angle with the free edges of folds 4 coinciding with the score lines 1^b, these folds resting directly upon the end walls 3, with the corner folds 5 resting directly upon their respective corner folds 4. Moreover, in this folding operation, referring to the particular box being described, the pairs of extensions 7 are caused to overlap each other and the same, together with the corner folds, folded as described, are held in such position in suitable manner, as by gluing, stapling or the like, but preferably by means of staples 9, as seen in Figs. 2, 3 and 4, after which the flaps 3^a which are of considerably less height than their walls 3 are folded downwardly and suitably secured at their middle to their walls and to the extensions 7. As herein shown, and by preference, the flaps 3^a overlie the folds 4 and 5 and are permanently secured intermediate their ends by means of eyelets 8 which may be found convenient for receiving the usual string or tape for fastening the lid onto the body of the box, but other means of fastening may be employed in place of eyelets, in all cases, however, the ends of the flaps 3^a being free to be flexed to permit the moving or swinging members of the corner folds to pass beneath the same in the operation of assembling the box and to be released when the box is being collapsed. The blank now assumes the condition illustrated in Fig. 2, in which form it is shipped to the consumer ready for his use.

In practice, the described box being in the flat or collapsed form, the operator simply folds up the end walls, with the result that, as indicated in Fig. 3, which represents the first opening movements of the collapsed box, the side walls, 2, 2 fold upwardly automatically by reason of the pressure exerted by the operator in folding the end walls upwardly and bringing them toward each other. At the same time, the corner folds 5 move upwardly and outwardly turning on the diagonal hinge connection with the corresponding fold 4 (in the described example the outer edges 5^a of folds 5 slipping along

the under face of the flaps 3^a) until they assume their position flat against the end walls 3, 3 with their outer faces or sides lying against the inner side of the end walls and with such edges 5^a of folds 5 positioned underneath the flaps 3^a and coinciding with their hinge joint with sides 3, it being understood that such flaps 3^a yield sufficiently toward their ends to permit of the described folding or movement of the corner folds 75 after which such flaps take their position inside of and covering the upper edges of such folds, thereby holding them in place. The box now assumes the condition illustrated in Fig. 4, the same being ready for 80 use.

The lid for the box above described may be of any suitable arrangement or construction, but I prefer to make the same on the same principle as the body of the box, to 85 which end, as illustrated in Fig. 5, such lid comprises a top 10, two pairs of side walls 11 and 12 hinged thereto, flaps 11^a on walls 11, sets of corner folds 13 and 14, and extensions 15 at each corner. Eyelets 16 or the 90 like secure together the flaps 11^a, extensions 15 and walls 11. In setting up the lid for use, the walls 11 are brought toward each other in the same manner as the walls 3 of the body of the box. 95

A hat box constructed and arranged as hereinbefore described is thus, as to each of its sections, that is the body and the lid, made of a single piece or blank with an entire bottom, or top, as the case may be, in 100 other words a bottom or top having no folds whatsoever, while two of the walls, in the present instance for convenience designated the end walls, may be formed of double thickness, so far as the body is concerned. 105 Moreover, in the present instance, the box body and lid are strengthened by the end flaps which fold over the top edges of the corner folds in the manner and for the purposes described, while the ends of the box 110 body are further strengthened by the extensions 7, 7 which therefore afford a triple thickness at the center line of the end walls of the box body without taking into consideration the additional thickness which is 115 provided along the top edge of the end walls by the presence of the flaps or extensions 3^a. Furthermore, the construction and arrangement provides for an automatic and rapid manipulation or setting up of the box from 120 its collapsed or flat form, this manipulation being simply the upfolding and the bringing toward each other of the end walls of the box, the side walls and corner folds springing up, as it were, into proper position without any effort or attention on the part of the operator except that required for folding up the end walls, as stated and being held in set-up position by the flaps 3^a of the opposite ends walls 3. 125 130

As hereinbefore stated, the string or tape for fastening the lid to the box body may be passed through or anchored in the eyelets 8 but if desired a special manner for threading the tape may be adopted having reference or useful application to the herein described particular form and manipulation of box. Such special threading is illustrated in Fig. 10, in which the fixed ends of the tapes 17 are shown secured to the extensions or flaps 3^a near their outer edges, such tapes preferably passing through eyelets 18 in such flaps, the tapes further passing upwardly along the outer sides or faces of the flaps 3^a and over the top thereof and alongside of the end walls 3 through openings 19 some distance down from the upper edges of the latter. The tapes are also passed through the overlapping extensions 7, 7 and 20 are then passed inwardly and over the lower edges of the flaps or extensions 3^a, back through the eyelet 18 and then through the openings or holes 20 in the extensions 7, 7, and end walls 3, the free ends of the tapes 25 being arranged on the outside of the box and being left of sufficient length to pass over the top of the box for the purpose of tying them together to hold on the lid in the usual and well known manner. However, this threading of the tape may be in 30 the reverse direction by starting with the tape at the same place as before, but extending the same around over the lower edge of the flap 3^a through the openings 19, thence upwardly along the outside surface of the end wall 3, over the top thereof, down the outer surface of the extension 3, through the eyelet and thence through the openings 20 to the outside of the box.

40 The above described arrangement or threading of the tapes provides a very efficient and desirable means, both for holding or anchoring the fixed ends of the tapes or strings and also for holding the flaps 3^a securely and firmly in proper position over the end walls 3, 3, as well as the tops of the corner folds, besides permitting the tapes to be easily loosened for the purpose of enabling a deep box to be set up.

45 My invention is equally well adapted for folding boxes other than hat boxes, by alteration in dimensions or proportions and other slight incidental changes that are obvious after the present disclosure of the principle 50 of my invention. For instance, my invention may be embodied in what is commonly known as a suit box or box commonly employed for the packaging of clothing and the like, as used by tailors, merchants, etc.

55 In Fig. 7, I have illustrated such embodiment of my invention in a suit box and have therein illustrated one of the members or sections of a box of that character, in which each section or half of the box comprises a part 60 21, representing the top or bottom, as the case may be, opposite side walls 22, opposite end walls 23, the four sets of corner folds 24 and 25, the four extensions 26 on the folds 24 and the end flaps 27 extending from the end walls 23. The extensions 26 do not meet or 65 overlap as is the case in respect to the first described box, but are separated some distance, owing to the width of the end walls 23, but such extensions are secured in place and in proper relation to the end walls, as 70 well as to the end extensions or flaps 27. In the present instance and by preference, these parts are secured together by pairs of eyelets 28 passing through the end flaps 27, extensions 26 and end walls 23. It is 75 obvious, after the foregoing description, that the act of bringing the end walls 23 toward each other serves to distend or set up the box in the same manner as the box illustrated in Figs. 2, 3 and 4. It will be 80 understood that the other half or companion section of the suit box is made either slightly larger or slightly smaller than that illustrated in Fig. 6, so that one will fit or telescope into the other, in the usual and well 85 known manner.

90 The marginal flaps on the body of the box illustrated in Figs. 1 to 4 extend inwardly as clearly illustrated in Fig. 4, and are intended to remain in such horizontal position by virtue of the strength of their hinging connection with their walls without any other support. However, it is desirable in some instances to provide means for so supporting these flaps, to which end I have 95 illustrated, in Fig. 8, a box whose marginal flaps 29 are provided at their ends with notches 30, which engage or interlock with 100 each other, and thereby serve to support each other, as well as to aid generally in 105 strengthening the box at its corners. The construction and arrangement is such that when the tape 31 which is passed through the flaps 29 and through the walls of the box, are drawn together, the middle portion 110 of the two opposite flaps 29, through which the strings or tapes are passed, is brought down close to the inner surface of either of the walls, but without disengaging the flaps at their interlocked ends.

115 It is obvious, after this disclosure of my invention, that the same may be embodied in still other forms and types of boxes and also that the folding may be done in somewhat different manner, all without departing from the spirit and scope of my invention. For instance the corner folds 4 and 5, instead of folding with their inner faces upon each other, may be arranged to fold with their outer faces upon or adjacent each 120 other. In this modified form of construction the extensions 7, 7 are omitted, as illustrated in Fig. 11, the triangular folds 32 and 33 being otherwise similar to the folds 4 and 5, already described except that 125

130

the folds 32 (only one of which is shown) are hingedly connected to the end walls 3 as shown by the score lines in Fig. 11. In practice, the corner folds 32 are turned over 5 inwardly and downwardly upon the end walls 3, with their respective inner surfaces or faces together and in order to permit of the setting up of the box in the general manner hereinbefore described, the corner 10 folds 32 are secured along their outer edges 32^a to the outer edges of the end walls 3. It will be apparent from an inspection of Fig. 3 that when the end walls of the box are folded toward each other, thereby elevating 15 the side walls and folding the corner folds 33 upwardly and outwardly, the corner folds 32 which are in fixed position with relation to the end walls 3 will rise and meet their companion corner folds when the 20 end walls are in their vertical position, it being understood that the outer sides or faces of the triangular folds are adjacent each other when the box is thus set up ready for use.

25 In assembling the box and also in bringing it to the flat or collapsed form illustrated in the drawings, the corner folds 4 are held to a fixed relation with respect to their adjacent end walls 3, and by this I 30 mean such a relation that the said corner folds 4 move with and not independently of the end walls, but it will be understood that this holding or retaining of such corner folds in such relation may be accomplished 35 in different ways without departing from the spirit and scope of my invention and claims. In the construction illustrated in Figs. 2, 3 and 4, the corner folds are not only held together through the medium of 40 the extensions 7, but are held connected by means of the eyelets to the end walls themselves. Again, as shown in Fig. 7, the fixed relationship of these corner folds with respect to the end walls is obtained by simply 45 securing them to such walls, while in Fig. 11 the outer edges 32^a of the corner folds 32 corresponding to the corner folds 4 of Fig. 1 may if desired be secured directly to the end walls 3 in suitable manner as by pasting, stapling and the like. It is obvious, 50 however, that these corner folds need not be secured or fastened to the end walls, but such fixed relationship otherwise secured, as by fastening the adjacent corner folds 4 55 together, as is shown in the modified form in Fig. 6, where the eyelet or other fastening is shown as passing simply through the extensions 7 and not through the end walls 3 and it is also obvious that the corner folds 60 32 illustrated in Fig. 11 after having been arranged beneath the flaps corresponding to the flaps 3^a of Fig. 1 will sustain fixed relationship to the end walls without any special fastening or securing means, as in the 65 movement of the end walls of the box in

assembling and collapsing the same the corner folds 32 do not pass from beneath said flaps, even though not directly secured or fastened to the end walls of the box.

It will be observed that in the setting up 70 of my improved box and in collapsing the same the corner folds 5 of Fig. 1 and the corresponding folds in the other figures of the drawing move on the diagonal hinge connection thereof with the companion 75 members of the corner folds, swinging to one side of said diagonal hinge line when the box is collapsed, as shown in Fig. 2, and to the other side of said line when the box is assembled as shown in Fig. 4, and other 80 corresponding figures of the drawings.

By the use of my invention, I am enabled not only to obtain the advantage of economy in stock or material and of convenience and ease in manipulation in setting up the 85 box ready for use, but also to dispense with the use of tongues and the like, which are objectionable in boxes of this character now in general use, not only because of the time in setting up the box, but also because of 90 the liability of one portion of the box catching in the tongue or slits, especially where the two portions of the box are intended to slide or telescope into each other. In my 95 form of box, the surfaces of the two portions which slide upon each other are smooth and do not present any interference one with the other, with the result that one portion may be easily telescoped into the other in the proper and intended manner. 100

The claims of this application generically cover the form of invention illustrated in Fig. 11, but such form is not herein specifically claimed, the same forming the subject matter of a divisional application filed 105 April 27, 1908, Serial No. 429,378.

I claim:

1. A collapsed box, comprising a base, a pair of side walls and a pair of end walls hingedly connected to the base along folding lines, one set of walls lying flat on the base with infolded portions at the ends thereof, flaps hingedly secured to the outer sides of the other set of walls, and means securing each flap between its ends to the wall upon which it is folded with the end portions of the flaps overlying the infolded portions. 110

2. A collapsed box, comprising a base, a pair of side walls and a pair of end walls hingedly connected to the base along folding lines, one set of walls lying flat on the base with infolded portions at the ends thereof, flaps of less height than said walls hingedly connected to the outer sides of the other set of walls and means securing each flap between its ends to the wall upon which it is folded. 120

3. A folding box comprising a bottom, 125 walls connected therewith, pairs of corner 130

- 5 folds, one member of each pair being hinged to a side wall and the other member being arranged, together with the similar member of the adjacent pair, in fixed relationship with respect to an end wall, and flaps on the end walls of less height than such walls, folded inwardly and downwardly upon the corner folds, secured intermediate their ends to the end walls, and having end portions free to be flexed to facilitate the setting up and collapsing of the box, substantially as described. 70
- 10 4. A folding box comprising a bottom, walls connected therewith, and pairs of corner folds, one member of each pair being hinged to a side wall and the other member being connected at its outer edge to an end wall, and flaps on the end walls of less height than such walls, folded inwardly and downwardly upon the corner folds, secured intermediate their ends to the end walls, and having end portions free to be flexed to facilitate the setting up and collapsing of the box, substantially as described. 75
- 15 5. A folding box comprising a bottom, walls connected therewith, and pairs of triangular corner folds, the members of each pair being hinged together, and one member being hinged to one of the side walls and the other member being folded over upon the adjacent or end wall and secured to the latter, and flaps on the end walls, said flaps being of less height than and secured to said walls, folded inwardly and downwardly 80 upon said corner folds, of less height than and secured intermediate their ends to the end walls, and having end portions free to be flexed to permit the setting up and collapsing of the box, substantially as de- 85
- 20 scribed. 90
- 25 6. A folding box comprising a bottom, walls connected therewith, and pairs of triangular corner folds, the members of each pair being hinged together, and one member being hinged to one of the side walls and the other member being folded over upon the adjacent or end wall and secured at its outer edge along substantially the middle vertical line of the latter wall, and flaps on 95 the end walls, said flaps being of less height than the end walls and secured at their middle portions thereto, and infolded upon the corner folds to maintain the latter in position, the ends of the flaps being free to be flexed to permit the setting up and collapsing of the box, substantially as described. 100
- 30 7. A folding box comprising a bottom 1, walls 2, 2 and 3, 3 hinged thereto, pairs of triangular-shaped corner folds 4, 5, the members of each pair being hinged to each other, the folds 5 being hinged to their walls 2, 2 and the folds 4 being separated from the edges of the walls 3, 3 by slits or cuts, extensions 7, 7, at the outer edges of the 105 folds 4, secured to each other and to the sides 3, 3 when the corner folds are folded inwardly, and flaps or extensions 3^a hinged on the walls 3, 3 and arranged to fold inwardly over the inturned corner folds, substantially as described. 110
- 35 8. A folding box comprising a bottom, walls hinged thereto, pairs of corner folds connected with the walls, flaps on two of the opposite walls folded inwardly toward their walls and upon said corner folds, and means for securing together each of said opposite walls and its flap and two adjacent corner folds, substantially as described. 115
- 40 9. A folding box comprising a bottom, walls hingedly connected thereto, plural member corner folds hingedly connected together and hingedly connecting said walls, flaps on opposite walls of the box of less height than said walls folded inwardly upon the corner folds, means permanently 120 securing said flaps intermediate the ends thereof, one member of each corner fold lying against the inner face of the flap-carrying walls beneath said flaps in all positions of said walls, and the other member of said corner folds moving upon the hinge connection between such corner fold members in setting up or collapsing the box, the end portions of said flaps being free to be flexed to receive the moving members of the 125 corner folds in setting up the box and to release the same in collapsing the box, substantially as described. 130
- 45 10. A folding box comprising a bottom, walls hingedly connected thereto, corner folds connected to opposite walls and arranged to lie against the inner faces of the adjacent walls, flaps on the last-mentioned walls of less height than said walls folded inwardly upon the corner folds, and means 135 permanently securing said flaps to said walls intermediate the ends of said flaps, the end portions of said flaps being free to be flexed to permit the setting up and collapsing of the box, substantially as de- 140
- 50 11. A folding box comprising a bottom, side and end walls hingedly connected thereto, corner folds, the members of which are hingedly connected together, one member of each of which lies against the inner face of the end walls of the box and serves to connect the other members of the corner folds thereto, said other members of each corner fold being also hingedly connected 145 to the side walls of the box and arranged to move into parallelism with said end walls at one side of the hinged connection therewith when the box is set up and into parallelism with said walls on the other side of 150 said hinged connection therewith when the box is collapsed, and flaps carried by and of less height than said end walls adapted to fold inwardly and permanently secured intermediate their ends to said end walls, the 155

end portions of said flaps being free to be flexed to receive and hold the movable members of the corner folds when the box is set up and permit said members to pass from engagement therewith when the box is collapsed, substantially as described.

12. A folding box comprising a bottom, walls hingedly connected thereto, corner folds composed of members hingedly connected together, one member of each corner fold lying against the inner face of opposite walls of the box in all positions of said walls, the other member of each corner fold hingedly connected to opposite walls of the 15 box to automatically move on its hinged

connections to permit the setting up or collapsing of the box, flaps carried by opposite walls of less height than said walls and permanently connected intermediate its ends to said walls, the ends of said flaps being 20 free to be flexed to engage over the movable corner fold members to hold the box in assembled form, and release said members to permit the box to be collapsed, substantially as described.
